Michael Bartholomew(57) **CLAIM**

The ornamental design for a portable karaoke speaker as shown and described.

DESCRIPTION

FIG. 1 is a front, right and top perspective view of a portable karaoke speaker, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, right and top perspective view of the portable karaoke speaker of FIG. 1 shown in a configuration of use; and,

FIG. 11 is a rear, left and top perspective view of the portable karaoke speaker of FIG. 10.

The dashed broken lines depict portions of the portable karaoke speaker that form no part of the claimed design. The dot-dash broken lines in FIGS. 1 and 9 depict the boundaries of the enlarged views and form no part of the claimed design.
